UNITED STATES PATENT OFFICE

2,419,510

HINGED COVER TRIANGULAR CARTON

Robert Van Rosen, New York, N. Y., assignor to
 J. Makowsky Corporation, a corporation of New
 York

Application June 6, 1945, Serial No. 597,734

9 Claims. (Cl. 229—22)

1

The invention relates particularly to a box or carton which may be used to contain any suitable or desirable article.

The device may be made of a single piece of material suitably cut and folded and even without pasting or other holding means.

An especial feature of the invention is the cover or closure member.

In the accompanying drawings a specific embodiment of the invention is shown. Figure 1 is a plan view of the blank from which the device may be folded. Figs. 2, 3 and 4 are perspective views of blanks in successive states of being partially folded to form the device. Fig. 5 is a perspective view of the completed device with the cover or closing member open. Fig. 6 is a perspective view of the completed device with the cover or closing member in closed position. Fig. 7 is a perspective view of a completed device in another specific form.

The device and the blank from which it is made, as well as the various elements or segments thereof, may be changed as to size, shape, proportions and cooperation in various ways, without departing from the invention, but a specific form will be explained in detail in connection with the drawings so as to fully disclose the invention.

The specific embodiment shown is triangular in shape and as shown the cover forms the front or top side of the device but it may be turned and used in any other position. Without limiting the use or construction of the device or the position of the various members but for convenience of description arbitrary terms of location will be employed. One wall will be referred to as the back wall, irrespective of where it may be positioned, and likewise walls and members will be referred to as right and left as they appear on the drawings. The various sections of the blank which make up the carton are of various sizes and shapes, some being longer in one direction and some in another, but for clearness of description the terms length and ends may be used with respect to the extent from top to bottom as shown in Fig. 1, while width or sides may be used with respect to extent from side to side as shown in Fig. 1. In Fig. 1 the blank from which the carton is to be formed is shown as a single sheet of cardboard or other suitable material. The solid lines of the drawing show lines on which cuts are made. The dot and dash lines show lines on which folds are made and these may be scored or otherwise prepared for easy and accurate folding or bending. The various portions of the blank may be referred to as members.

The member 10 is to form the back of the finished carton and at its right side may be attached the outer right wall member 11 to which is attached the right inner wall member 12. To

2

the left of the back wall member 10 is attached the outer left wall member 13 to which is attached the inner left wall member 14. To the top of the back wall member is attached the top or cover member 15 at either side of which are attached wing members 16, 17 which are provided at their outer ends with teeth or serrations 18, 19 for a purpose to be hereinafter explained. To the top end of the cover 15 is attached a tab or finger member 20. At the bottom edge of the outer right wall member 11 is attached an intermediate bottom wall member 21 and attached to the bottom of the outer left wall member 13 is an intermediate bottom wall member 22. One of the interlocking members such as 21 may be cut away or curved as at 23 so as to facilitate interlocking.

The first step in forming the carton may be as shown in Fig. 2 where the members 12 and 14 are folded over onto the members 11 and 13, respectively, and the wing members 16 and 17 may be turned up. The combined side members 11, 12 and 13, 14 may then be turned up as shown in Fig. 3 and the members 21 and 22 caused to interlock.

At the bottom of the back member 10 is attached an outer bottom member 24 which may now be turned upwardly or forwardly to lie as shown in Fig. 4 in close contact with the interlocked members 21, 22 and cover and protect the interlocking joint and form a smooth outer surface. The member 24 may be cut away at its sides as at 25 so that in the finished box as shown in Fig. 6 the sides of the outer bottom wall member 24 may not be visible.

At the front or bottom edge of the member 24 is attached the inner bottom panel wall member 26 which has on each side at its bottom end side tabs or wings 27 which may be turned downward as shown at Fig. 3. The member 26 may now be turned inward to overlie the intermediate bottom member 21, 22 as indicated in Fig. 5, in which position the wings 27 will rest against the inner side wall members 12 and 14.

The inner bottom member 26 carries at the sides of its upper or front end teeth or serrations 28 and the top or cover member 15 may now be bent forward inserting the wings 16, 17 between the edges of the inner side walls 12 and 14 so that the teeth or serrations 18, 19 carried by the wings 16, 17 will engage the teeth or serrations 28 and so tend to hold the cover closed and in place. The tab 20 will rest against the front edge of the bottom as indicated in Fig. 6 and may serve as means for lifting the locking teeth out of engagement and also as a handle for raising or opening the cover member 15.

A tab 29 may be cut and turned up in the inner bottom wall member 26 as shown in Fig. 5 and form a stop or positioning means for a bottle

or other device (not shown) which may be contained in the carton.

The material of which the device is made may be somewhat resistant to bending so that it has a tendency to resume its unfold or flat position. Thus the inner side walls 12 and 14 press against the inner bottom wall member 26 and tend to hold it in place. The wings 27 may also press against the inner wall members 12 and 14 and tend to hold the inner wall members in close contact with the outer wall members 11 and 13 and also hold the bottom member 26 snugly in place. When the cover 15 is in place the wings 16 and 17 may tend to spread and, by pressure contact with the side wall members 12 and 14, tend to hold the cover in closed position indicated in Fig. 6. In order to allow it to assume its proper position the cover member 15 may be slightly narrower than the back wall member 10. The inner bottom wall member 26 may be slightly narrower than the combined interlocking members 21 and 22.

It will be observed when the carton is open as shown in Fig. 5 or closed as in Fig. 6 no rough or cut edges are shown. A neat attractive finish is furnished by exposing at the sides the curved folded edges between the members 11 and 12 and between the members 13 and 14 and at the bottom the curved folded edge between the members 24 and 26.

The succession of folding the various members described may be a convenient order, but it is not essential to the present invention since the parts may be folded and brought into contact with each other in other orders to produce the carton.

Fig. 6 shows a carton made from the blank shown in Fig. 1. By properly varying the shapes and sizes of the elements cartons of other shapes and sizes may be produced, one of these being shown in Fig. 7.

I claim as my invention:

1. In a carton formed from a single sheet of material, a back member, an outer triangular right side member articulated to the right side of the back member, an inner triangular right side member articulated to the hypotenuse of the outer right side member and lying parallel thereto, a locking member articulated to the lower side of the right outer side member, an outer triangular left side member articulated to the left side of the back member, an inner inner triangular left side member articulated to the hypotenuse of the outer left side member and lying parallel thereto, a locking member articulated to the lower side of the left outer side member interlocked with the locking member articulated to the lower side of the right side member one of said locking members having a beveled inner end to facilitate interlocking and said interlocking members forming an intermediate bottom wall member, an outer bottom wall member articulated at one end of the bottom of the back member and underlying the interlocking members but of less width than the interlocking members, an inner bottom wall member articulated at the other end of the outer bottom wall member and overlying the interlocking members, upwardly extending wings articulated to the inner bottom wall member resting against and holding in place the inner side wall members, a projecting stop member in the inner bottom wall member, teeth at each side of the forward end of the inner bottom wall member, a front wall member narrower than the back wall member and articu-

lated to the top thereof, wings articulated at each side of the front wall member and at right angles therewith lying between the inner side walls and in contact therewith, teeth on the lower ends of the last mentioned wings engaging the teeth on the inner bottom wall member, and a projecting tab at the lower end of the front wall member.

2. In a carton formed from a single sheet of material, a back member, an outer triangular right side member articulated to the right side of the back member, an inner triangular right side member articulated to the hypotenuse of the outer right side member and lying parallel thereto, a locking member articulated to the lower side of the right outer side member, an outer triangular left side member articulated to the left side of the back member, an inner triangular left side member articulated to the hypotenuse of the outer left side member and lying parallel thereto, a locking member articulated to the lower side of the left outer side member interlocked with the locking member articulated to the lower side of the right side member, said interlocking members forming an intermediate bottom wall member, an outer bottom wall member articulated at one end to the bottom of the back member and underlying the interlocking members but of less width than the interlocking members, an inner bottom wall member articulated at the other end of the outer bottom wall member and overlying the interlocking members, upwardly extending wings articulated to the inner bottom wall member resting against and holding in place the inner side wall members, a front wall member narrower than the back wall member and articulated to the top thereof, and wings articulated at each side of the front wall member and at right angles therewith.

3. In a carton formed from a single sheet of material, a back member, an outer triangular right side member articulated to the right side of the back member, an inner triangular right side member articulated to the outer right side member and lying parallel thereto, a locking member articulated to the lower side of the right outer side member, an outer triangular left side member articulated to the left side of the back member, an inner triangular left side member articulated to the outer left side member and lying parallel thereto, a locking member articulated to the lower side of the left outer side member interlocked with the locking member articulated to the lower side of the right side member, said interlocking members forming an intermediate bottom wall member, an outer bottom wall member articulated at one end to the bottom of the back member and underlying the interlocking members, an inner bottom wall member articulated at the other end of the outer bottom wall member and overlying the interlocking members, upwardly extending wings articulated to the inner bottom wall member resting against and holding in place the inner side wall members, and a front wall member articulated to the top of the back wall member.

4. In a carton formed from a single sheet of material, a back member, a right side member articulated to the right side of the back member, a locking member articulated to the lower side of the right side member, a left side member articulated to the left side of the back member, a locking member articulated to the lower side of the left side member interlocked with the locking member articulated to the lower side of the right side member, said interlocking members forming

an intermediate bottom wall member, an outer bottom wall member articulated at one end to the bottom of the back member and underlying the interlocking members, an inner bottom wall member articulated at the other end of the outer bottom wall member and overlying the interlocking members, upwardly extending wings articulated to the inner bottom wall member resting against the side wall members, teeth at each side of the forward end of the inner bottom wall member, a front wall member narrower than the back wall member and articulated to the top thereof, wings articulated at each side of the front wall member and at right angles therewith lying between the side walls and in contact therewith, and teeth on the lower ends of the last mentioned wings engaging the teeth on the inner bottom wall member.

5. In a carton formed from a single sheet of material, a back member, an outer right side member articulated to the right side of the back member, an inner right side member articulated to the outer right side member and lying parallel thereto, a locking member articulated to the lower side of the right outer side member, an outer left side member articulated to the left side of the back member, an inner left side member articulated to the outer left side member and lying parallel thereto, a locking member articulated to the lower side of the left outer side member interlocked with the locking member articulated to the lower side of the right side member, said interlocking members forming an intermediate bottom wall member, an outer bottom wall member articulated at one end to the bottom of the back member and underlying the interlocking members, an inner bottom wall member articulated at the other end of the outer bottom wall member and overlying the interlocking members, upwardly extending wings articulated to the inner bottom wall member resting against and holding in place the inner side wall members, teeth at each side of the forward end of the inner bottom wall member, a front wall member narrower than the back wall member and articulated to the top thereof lying between the inner side walls and in contact therewith, and teeth on the lower ends of the last mentioned wings engaging the teeth on the inner bottom wall member.

6. In a carton formed from a single sheet of material, a back member, an outer triangular right side member articulated to the right side of the back member, an inner triangular right side member articulated to the hypotenuse of the outer right side member and lying parallel thereto, a locking member articulated to the lower side of the right outer side member, an outer triangular left side member articulated to the left side of the back member, an inner triangular left side member articulated to the hypotenuse of the outer left side member and lying parallel thereto, a locking member articulated to the lower side of the left outer side member interlocked with the locking member articulated to the lower side of the right side member, said interlocking members forming a bottom wall member, a bottom wall member articulated to the back member and overlying the interlocking members, upwardly extending wings articulated to the bottom wall member resting against and holding in place the inner side wall members, teeth at each side of the forward end of the bottom wall member, a front wall member narrower than the back wall member and

articulated to the top thereof, wings articulated at each side of the front wall member and at right angles therewith lying between the inner side walls and in contact therewith, and teeth on the lower ends of the last mentioned wings engaging the teeth on the bottom wall member.

7. In a carton formed from a single sheet of material, a back member, an outer right side member articulated to the right side of the back member, an inner right side member articulated to the outer right side member and lying parallel thereto, a locking member articulated to the lower side of the right outer side member, an outer left side member articulated to the left side of the back member, an inner left side member articulated to the outer left side member and lying parallel thereto, a locking member articulated to the lower side of the left outer side member interlocked with the locking member articulated to the lower side of the right side member, said interlocking members forming an intermediate bottom wall member, an outer bottom wall member articulated at one end to the bottom of the back member and underlying the interlocking members, an inner bottom wall member articulated at the other end of the outer bottom wall member and overlying the interlocking members, upwardly extending wings articulated to the inner bottom wall member resting against and holding in place the inner side wall members, teeth at each side of the forward end of the inner bottom wall member, a front wall member narrower than the back wall member and articulated to the top thereof lying between the inner side walls and in contact therewith, and teeth on the front wall member engaging the teeth on the inner bottom wall member.

8. In a box having four sides, a cover articulated to one side, wings articulated to each side of the cover and lying between the sides of the box adjacent the side to which the cover is articulated, serrations in the ends of the wings, an inner panel member in the side of the box opposite the side to which the cover is articulated, and serrations in the edges of the inner member cooperating with the first mentioned serrations when the cover is closed to hold the cover closed.

9. In a box having four sides, a cover articulated to one side, wings articulated to each side of the cover and lying between the sides of the box adjacent the side to which the cover is articulated, serrations in the ends of the wings, an inner panel member in the side of the box opposite the side to which the cover is articulated, serrations in the edges of the inner member cooperating with the first mentioned serrations when the cover is closed to hold the cover closed, and a projecting tab on the cover overlying the side of the box opposite to the side to which the cover is articulated acting as a handle to disengage the serrations and lift the cover.

ROBERT VAN ROSEN.
